UNITED STATES PATENT OFFICE.

ALBERT PETER AHLES, OF ROME, NEW YORK, ASSIGNOR TO FORT STANWIX TOOL AND DIE CO., OF ROME, NEW YORK.

FOLDABLE STOOL.

Application filed November 24, 1926. Serial No. 150,613.

The invention relates to a stool and more especially to the class of foldable step-ladder stools or a combination stool and step-ladder of the foldable type.

- 5 The primary object of the invention is the provision of an article of this character, wherein the construction thereof enables the stool to be utilized as a step-ladder, the steps being supported in swinging relation to the 10 stool, so that when not in use the same will be concealed within the stool, the ladder and the steps being constructed from metal to give rigidity and strength to the article, so that it may withstand severe usage.
- 15 Another object of the invention is the provision of an article of this character, wherein the steps are foldably connected with the stool, in a manner, that when the steps are swung outwardly from within the stool they 20 will be materially braced to sustain the same rigid for use and when not in use can be confined or concealed within the stool, the article being of novel form.

25 A further object of the invention is the provision of an article of this character, which is extremely simple in construction, thoroughly reliable and efficient in its purposes, strong, durable, neat and attractive in appearance, readily portable and inexpensive 30 to manufacture.

With these and other objects in view, the invention consists in the features of construction, combination and arrangement of parts, as will be hereinafter more fully described in detail, illustrated in the accompanying drawing, and pointed out in the claims hereunto appended.

In the accompanying drawing:

Figure 1 is a vertical sectional elevation 40 taken on line 1—1 of Figure 2 through the article, constructed in accordance with the invention, showing by full lines the steps extended for use and by dotted lines the same concealed within the stool.

45 Figure 2 is a front elevation of the stool with the steps in position for use.

Similar reference characters indicate corresponding parts throughout the several views in the drawing.

50 Referring to the drawing in detail, A designates generally the stool and B the steps of the combination article constituting the subject matter of the present invention. The stool A comprises corner legs 5, these 55 being four in number, arranged in pairs and

each is preferably made from metal, although the same may be made from any other suitable material, of the required length to give the desired height to the stool. The legs 5 converge upwardly and support 60 at their top ends a seat section 6 preferably made from sheet metal having a marginal depending flange 7 continuous and unbroken at the corners thereof. Passed through the flange 7 are rivets or fasteners 8, which 65 secure the legs 5 to the seat 6 as will be clearly apparent from Figures 1 and 2 of the drawing.

Cross braces are employed for holding the legs rigid. The cross braces are arranged 70 in pairs, one pair positioned above the other pair. The cross braces of one pair indicated at 9 connect the legs of one pair of legs to the legs of the other pair of legs. The other pair of cross braces are indicated 75 at 10 and each is provided for connecting the legs of a pair of legs together. The cross braces 10 are positioned against the inner sides of the legs. The cross braces 9 are positioned against the outer edges of the legs 80 and above the braces 10. One of the cross braces 9 provides a seat for the purpose to be presently referred to.

The steps B comprise companion side plates 85 11 having mounted thereon the step sections 12, the plates 11 being cut into to provide the risers for the step sections 12. The plates 11 and the step sections 12 are preferably made from metal, although the same may be made from any other suitable material and 90 are united to each other to constitute a unitary structure.

Swingingly connected to the side braces 10 of the stool A close to the rear ends of said braces are opposed swinging links 13, 95 these being also pivoted at 14 to the plates 11 near their rear edges. The links 13 are of sufficient length to bring the steps B to the position from full lines in Figure 1 of the drawing to the position of the dotted lines, 100 whereby the top step section 12 will abut the flange 7 of the seat 6 at the rear stretch of said flange 7, whereby the steps B will be concealed or confined within the stool A as will be clearly obvious.

105 The rear edges of the plates 11 of the steps B at a determined point are formed with cutout portions or notches 15 to constitute shoulders for seating on or abutting the cross front brace 9 when the steps have 110

been moved outwardly of the stool A or to the full line position shown in Figure 1 and in this manner the links 13 and the front cross brace 9 will rigidly support the steps B in extended position relative to the stool A.

The lower portions of the plates 11 constitute feet 16 for the steps B when the latter are extended or swung outwardly relative to the stool A as will be noted.

From the foregoing it is thought that the construction and manner of use of the article hereinbefore described will be clearly understood and therefore a more extended explanation has been omitted.

What is claimed is:—

1. An article of manufacture of the character described, comprising a seat, spaced legs for supporting said seat, upper and lower cross braces connecting said legs together, a step section movable within and without the space between said legs and having each side thereof provided with a shoulder for seating on one of the upper cross braces when the step section is extended, pivot links swingingly connected to the lower cross braces and pivotally connected to the

sides of the step section and projecting over said cross brace associated with said shoulders when the step section is extended, and feet extensions on the sides of the step section for supporting the latter when extended.

2. An article of manufacture of the character described, comprising a seat provided with a depending marginal flange, spaced legs for supporting said seat and secured to said flange, upper and lower cross braces connecting said legs together, a step section movable within and without the space between said legs and having each side thereof formed with a shoulder for seating on one of said upper cross braces when the step section is extended, pivot links swingingly connected to the lower cross braces and pivotally connected to the sides of the step section, and feet extensions on the sides of the step section for supporting it when extended, said step section when in non-extended position abutting said marginal flange.

In testimony whereof, I affix my signature hereto.

ALBERT P. AHLES.
